UNITED STATES PATENT OFFICE.

JACOB STRAND, OF NEW YORK, N. Y.

PIPE COLLAR OR RING.

SPECIFICATION forming part of Letters Patent No. 758,870, dated May 3, 1904.

Application filed January 2, 1904. Serial No. 187,467. (No model.)

To all whom it may concern:

Be it known that I, JACOB STRAND, a citizen of the United States, residing in Manhattan borough, New York city, in the county of New York and State of New York, have invented certain new and useful Improvements in Pipe Collars or Rings, of which the following is a specification.

This invention relates to rings or collars which are designed to be used in connection with stove, steam, or other pipes to effect a finish where the pipe enters an opening.

The object of this invention is to provide a ring which may be adjusted to fit pipes of various diameters and also to produce an inexpensive and efficient device.

The drawings accompanying the present specification illustrate an embodiment of my invention, in which—

Figure 1 illustrates a strip of sheet metal bent upon itself to form a ring and shows one end in dotted lines. Fig. 2 illustrates the same bent upon itself to form a ring, the inner diameter of which is smaller than the one shown in Fig. 1; and Fig. 3 is a detail showing one of the tongues or prongs around the inner side of the rings bent outwardly.

Similar characters of reference indicate like parts throughout the figures.

A strip of sheet metal is bent upon itself to form a ring 1, which in the present instance is stamped or otherwise formed to produce struck-up projections 2, serving as ornamentalations, all of which are preferably alike, and this strip along one edge is provided with a plurality of scallops or prongs 3, which extend outwardly in pairs from the base of said projections. Near one extremity of the strip is an opening 4, and for a certain distance along the strip at its other end is a plurality of holes 5, 6, and 7, and all of these holes are preferably located in a line along the longitudinal axis of the strip and preferably between the struck-up portions 2 aforementioned. When the ends of the strips are overlapped—for instance, as seen in Fig. 1—to form the ring, the outer portion of the struck-up portions 2 on one portion of the strip will register or lie into the inner portion of the struck-up portion on the other end of the

strip, and in this way there is an interlocking relation between the two ends of the strip, besides that locking which is accomplished by means of the cleat 8, which is passed through the opening 4 and any of the other openings 5, 6, 7, 9, 10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100.

This ring may be fitted around the ordinary-size pipe by suitable adjustments thereof.

It is to be understood, of course, that the ring may be made in various sizes, each size being adjustable to various other sizes within limits, so as to provide for the fitting of very small to very large pipes. It will also be seen that while the invention primarily may be directed to stovepipe-collars, yet the same may be also applied to collars which are used around water-pipes, drain-pipes, steam-pipes, and the like.

Having thus described my invention, I claim—

1. As an article of manufacture, an element

bent upon itself to form a ring having projections extending outwardly from the face of said element, and prongs proceeding from the base of each projection and around the inner edge of said ring, and having a slit between each pair of prongs which extends into the top of a corresponding projection, and means for locking the ends of said element when in different overlapped positions.

- 10 2. As an article of manufacture, an element bent upon itself to form a ring and provided with projections extending outwardly from the face of said element, and with prongs proceeding from the base of each projection and around the inner edge of the ring and having a slit between each pair of prongs which extends into the top of the corresponding projection, and a cleat for locking the ends of said element when in different overlapped positions.
- 15 3. A stovepipe-ring comprising a split member whose free ends are adapted to overlap in

different positions to form a ring of different diameters and having prongs around said ring in the inner edge thereof, and struck-up portions around the face of said ring, the face of some of which when the ends are overlapped take into the hollows of others, and means for locking the overlapped ends.

4. A stovepipe-ring comprising a split member whose free ends are adapted to overlap in different positions to form a ring of different diameters and prongs around the inner edge thereof, of struck-up portions around the face of said ring, the faces of some of which, when the ends are overlapped, take into the hollows of others, and a cleat for locking the overlapped ends.

Signed at Nos. 9 to 15 Murray street, New York, N. Y., this 30th day of December, 1903.

JACOB STRAND.
